UNITED STATES PATENT OFFICE.

GEORGE W. NIXON, OF ROCKWOOD, ASSIGNOR TO HIMSELF AND WM. M. NIXON, OF CHATTANOOGA, TENNESSEE.

SUPPORT FOR ROCK-DRILLS.

SPECIFICATION forming part of Letters Patent No. 325,564, dated September 1, 1885.

Application filed April 27, 1885. (No model.)

To all whom it may concern:

Be it known that I, GEORGE W. NIXON, a citizen of the United States, residing at Rockwood, in the county of Roane and State of Tennessee, have invented a new and useful Improvement in Rock-Drill Supports, of which the following is a description.

This invention relates to that class of devices which are used for drilling holes in the process of coal-mining and sinking shafts in rock, &c.; and its object is to provide a base against which a drill propelled by a ratchet-lever or similar device may push to force itself into the rock, and to provide means whereby the ratchet-drill may be quickly readjusted after it has extended to its limit.

To this end my invention consists in the construction and combination of parts forming a rock-drill support, hereinafter described and claimed, reference being had to the accompanying drawings, in which—

Figure 1 is a longitudinal vertical section of a mine-shaft, showing my invention in side elevation. Fig. 2 is a longitudinal section of the support; and Fig. 3 is a transverse section of the support, showing, also, a portion of a ratchet-drill and the supporting-dog.

A represents a shaft in a rock, B. C is a drill secured in a ratchet-drill stock, D, to be revolved in drilling by a reciprocating motion of the stock.

E represents the body of my support, consisting of a metal pipe pointed at one end to rest in a small cavity to be made in the wall of the shaft for that purpose, and re-enforced at the other end by a collar or ferrule, F, to give it strength and to furnish sufficient thickness to hold a set-screw, G.

H is a smaller metallic tube, fitted to telescope within the tube E, and adapted to be extended therefrom and to be rigidly fixed

thereto by the set-screw G. By this means the support may be quickly lengthened, so as to extend nearly across the shaft A.

J is a screw, threaded into the outer end of the tube H, to be stepped in a small hole made in the wall for that purpose.

K is a hand-lever, by which the tube H is revolved around the screw, to extend or retract the screw the amount necessary to fit the support tightly between the two walls of a shaft.

As the tubes H and E may be set to very nearly reach across the shaft, the screw J need not be more than three inches long for general use.

The end of the tube E has a turned conical point, while the outer end of the screw J is not pointed, so that the screw will stick against the rock while the tube turns thereon.

The ratchet-drill stock D is provided with the usual screw-sleeve, L, from which the screw M is gradually extended, to advance the drill C into the rock while drilling.

N is a sleeve, having a set-screw, P, by which it may be secured at any point along the sleeve of the drill-stock, and having a curved arm, O, to press against and partly encircle the body E of the support.

What I claim as my invention, and desire to secure by Letters Patent, is—

The combination of the extensible support described, the drill-stock having a stationary sleeve, L, and the sleeve N, adapted to encircle the sleeve L, and provided with the set-screw P and with the curved arm O, the latter adapted to partly encircle the said support, substantially as shown and described.

GEORGE W. NIXON.
